Primary Examiner — Susan Bennett Hattan*Assistant Examiner* — Charles Hanson(74) Attorney, Agent, or Firm — LeClairRyan(57) CLAIM

The ornamental design for tool box, as shown and described.

DESCRIPTION

FIG. 1 is a perspective view of tool box showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The portions shown in dashed line do not form part of the design.
